UNITED STATES PATENT OFFICE.

FREDERICK W. CHRISWELL, OF SEATTLE, WASHINGTON, ASSIGNOR TO PACIFIC CAR AND FOUNDRY COMPANY, OF SEATTLE, WASHINGTON, A CORPORATION OF WASHINGTON.

LOG BUNK.

Application filed July 15, 1924. Serial No. 726,118.

To all whom it may concern:

Be it known that I, FREDERICK W. CHRISWELL, a citizen of the United States of America, and resident of the city of Seattle, 5 in the county of King and State of Washington, have invented certain new and useful Improvements in Log Bunks, of which the following is a specification.

My invention relates to log bunks designed 10 for mounting upon trucks, cars and the like, for purpose of supporting and carrying logs during transit.

The object of my invention is to provide 15 a type of construction for these logs which shall be strong and simple, employing standard sizes and types of material, and one which is also designed for satisfactory holding of the logs.

My invention consists of a bunk in which 20 the vertical webs are made of two sections of rolled steel in the form of bulb angles connected by a rolled section in the form of a channel bar, these being assembled in such manner as to provide a channel above the 25 web of the connecting channel bar and between the upper ends of the bulb angles, in which is mounted and held the chock.

The type of construction which is preferred by me is shown in the accompanying 30 drawings.

Figure 1 is a top or plan view of a bunk made in accordance with my invention.

Figure 2 is a side elevation of the same 35 bunk with one of the side webs broken away near one end to show its interior construction.

Figure 3 is an end elevation of the bunk.

In making this bunk I employ two bulb 40 angles 1, placed with their webs vertical, with a flange 10 at the bottom and extending outwardly. This brings the bulb 11 of each angle at the top. Between these bulb angles is secured a channel bar 2, this being placed so that its web is located somewhat 45 below the upper edge of the bulb angles and with the flanges of the channel bar extending downwardly. Locating these parts in the manner described provides a channel above the web of the channel bar, in which 50 is placed the log-holding chocks 3. The upwardly projecting edges of the bulb angles restrain the chock against movement laterally. The chock is provided with a downwardly extending arm to which is con-

nected a chain 5. The web of the channel 55 bar 2 is also provided with a slot 20 near each end for the reception of the arm 30 of the chock. The chock holding chain 5 extends to the opposite end of the bunk, passing through the enlarged end of a slot 40 60 formed in a diaphragm or partition plate 4 which is secured between the webs of the bulb angles. This slot 40 is provided with the reduced section 41 at one side, into which a link of the chain is inserted in order to 65 restrain the endwise movement of the chain, and thereby hold the chock against outward movement. To more fully secure the chain in this position it is carried about the end of the bunk and dropped into a slot 60 70 formed in a chain-retaining member 6 secured to the outer face of the bulb angle 1.

By using a channel bar 2 as the connecting web for the bulb angles, the channel thus 75 formed, and in which are mounted the log chocks 3, has vertical surfaces next to the chock. In consequence the chock may be made to closely fit between the upper ends of the two bulb angles and it is held securely in place against any lateral movement or twisting, and is yet free to move lengthwise of the bunk.

What I claim as my invention is:

1. A log bunk comprising two bulb-angles and a channel bar secured to and between 85 the bulb-angles with its web somewhat below the bulbs of the angles and with the flanges of the channel bar downward.

2. A log bunk comprising two bulb-angles and a channel bar secured to and between 90 the bulb-angles with its web below the bulbs and its flanges downward, the web of the channel bar having a slot therein near each end to accommodate chock holding chains.

3. A log bunk comprising two bulb angles and a channel bar secured to and between 95 the bulb angles with its web a short distance below the bulbs to provide a chock receiving channel, the flanges of the bulb angles extending outwardly and of the channel bar 100 downwardly, the web of the channel bar near each end having slots accommodating chock holding chains, and chain holding dogs at the ends of the bunk.

Signed at Seattle, King County, Wash- 105 ington, this 10th day of July 1924.

FREDERICK W. CHRISWELL.
